Primary Examiner — Darlington Ly(57) **CLAIM**

The ornamental design for a cordless microphone, as shown and described.

DESCRIPTION

1. Cordless microphone
1.1 is a front view of a cordless microphone showing my new design;
1.2 is a rear view thereof;
1.3 is a rear view thereof, wherein the clip is rotated outward to the left side of the cordless microphone;
1.4 is a left side view thereof;
1.5 is a right side view thereof;
1.6 is a top view thereof;
1.7 is a bottom view thereof;
1.8 is a bottom, rear, and left side perspective view thereof; and
1.9 is a top, front, and right side perspective view thereof.

1 Claim, 9 Drawing Sheets(56)
